DESIGN FOR A SAND URN

Wilbur Henry Adams, Millcreek Township, Erie
County, Pa., assignor to The F. H. Lawson
Company, Cincinnati, Ohio, a corporation of
Ohio

Application September 18, 1941, Serial No. 103,404

Term of patent 7 years

To all whom it may concern:

Be it known that I, Wilbur Henry Adams, a citizen of the United States, and a resident of Millcreek Township, in the county of Erie and State of Pennsylvania, have invented a new, original, and ornamental Design for a Sand Urn, of which the following is a specification, reference being had to the accompanying drawing, forming a part thereof.

In the drawing:

Figure 1 is a side elevational view of a sand urn, showing my new design.

Figure 2 is a top plan view thereof.

Figure 3 is a partial sectional view taken vertically along the line 3—3 of Figure 2.

Figure 4 is a partial horizontal sectional view through the body of the device taken along the line 4—4 of Figure 1.

I claim:

The ornamental design for a sand urn, substantially as shown.

WILBUR HENRY ADAMS.
